UNITED STATES PATENT OFFICE

98,931

DESIGN FOR A BOTTLE

William J. Gerber, Jr., Tell City, Ind.

Application January 9, 1936, Serial No. 60,491

Term of patent 7 years

To all whom it may concern:

Be it known that I, William J. Gerber, Jr., a citizen of the United States, residing at Tell City, in the county of Perry and State of Indiana, have invented a new, original, and ornamental Design for a Bottle, of which the following is a specification, reference being had to the accompanying drawing, forming a part thereof.

In the drawing,

Fig. 1 is a top plan view of a bottle showing my new design; and

Fig. 2 is a side view of the same.

I claim:

The ornamental design for a bottle, as shown.

WILLIAM J. GERBER, JR.
